DESIGN FOR A HAT

Samuel Scheuer, New York, N. Y.

Application September 7, 1935, Serial No. 58,467

Term of patent 3½ years

To all whom it may concern:

Be it known that I, Samuel Scheuer, a citizen of the United States of America, residing in Manhattan, county of New York, and State of New York, have invented a new, original, and ornamental Design for a Hat, of which the following is a specification, reference being had to the accompanying drawing, forming part thereof, wherein,

Figure 1 is a plan view of a hat showing my new design.

Figure 2 is a side elevational view of a hat showing my new design.

The characteristic feature of my new design resides in the stitching on the double brim.

The dominant feature of my design for a hat, resides in the overlapping semi-circles stitched on the brim.

I claim:

The ornamental design for a hat as shown and described.

SAMUEL SCHEUER.
